UNITED STATES PATENT OFFICE.

JOZEEFA KECZUR, OF WEST SELKIRK, CANADA.

DESIGN FOR A CHIPPED-GLASS TABLE ORNAMENT.

Application filed December 12, 1922. Serial No. 4,582. Term of patent 7 years.

To all whom it may concern:

Be it known that I, JOZEEFA KECZUR, a citizen of Ukraine, residing at West Selkirk, in the Province of Manitoba and Dominion of Canada, have invented a new, original, and ornamental Design for Chipped-Glass Table Ornament, of which the following is a specification, reference being had to the accompanying drawing, forming part thereof.

The figure is a front elevational view of a chipped glass table ornament, showing my new design.

I claim:—

The ornamental design for a chipped glass table ornament, as shown.

JOZEEFA KECZUR.
